UNITED STATES PATENT OFFICE

JOSEPH BIELSKI, OF CHICAGO, ILLINOIS, ASSIGNOR TO FEDERAL ELECTRIC COMPANY, INC., OF CHICAGO, ILLINOIS, A CORPORATION OF NEW YORK

DESIGN FOR A SIGN

Application filed October 31, 1930. Serial No. 37,483. Term of patent 7 years.

To all whom it may concern:

Be it known that I, JOSEPH BIELSKI, a citizen of the United States, residing in Chicago, in the county of Cook and State of Illinois, have invented a new, original, and ornamental Design for a Sign, of which the following is a specification, reference being had to the accompanying drawing, forming part thereof.

In the drawings:—

It is to be understood that the unfinished portions of the figure, as illustrated, involve a mere repetition of the completed portions, as shown on the left of the figure.

I claim—

The ornamental design for a sign, as shown and described.

In testimony whereof I claim the foregoing as my invention, I affix my signature this 28th day of October, 1930.

JOSEPH BIELSKI.
